No. 824,011.

PATENTED JUNE 19, 1906.

J. HANSER.

VALVE GEAR FOR ENGINES.

APPLICATION FILED JUNE 7, 1905.

UNITED STATES PATENT OFFICE.

JOSEPH HANSER, OF MANHEIM, TEXAS.

VALVE-GEAR FOR ENGINES.

No. 824,011.

Specification of Letters Patent.

Patented June 19, 1906.

Application filed June 7, 1905. Serial No. 264,185.

To all whom it may concern:

Be it known that I, JOSEPH HANSER, a citizen of the United States of America, residing at Manheim, in the county of Lee and State 5 of Texas, have invented new and useful Improvements in Valve-Gear for Engines, of which the following is a specification.

This invention relates to steam-engines, and especially to a reversing mechanism 10 therefor; and has for its objects to produce a comparatively simple inexpensive device of this character which may be readily installed for use, one whereby the direction of rotation of the engine-shaft may be reversed, and 15 one in which the engine may be stopped when circumstances require.

Further objects of the invention are to provide a simple and efficient member for connecting the valve-stem on the frame and for 20 guiding the same in its movements and to produce an improved form of rocking member having means for engaging the connecting-rod and guiding the latter in its movements.

25 With these and other objects in view the invention comprises the novel features of construction and combination of parts more fully hereinafter described.

In the accompanying drawings, Figure 1 is 30 a side elevation of an engine equipped with a governing mechanism embodying the invention. Fig. 2 is a perspective view of the valve-stem guide, and Fig. 3 is a perspective view of the rocking member or bell-crank lever.

35 Referring to the drawings, 1 designates the engine-frame, in which is journaled a shaft 2, provided with a crank arm or pin 3, on which is pivoted one end of a pitman 4, connected 40 at its other end with the piston-rod, (not shown,) said rod being equipped, as usual, with a piston-head movable in a cylinder 5.

The foregoing parts are of the usual or any appropriate construction and material and 45 adapted to operate in the ordinary manner.

Fixed upon the shaft 2 is an eccentric-head 6, engaged by an eccentric-strap 7, carrying an eccentric-rod 8, pivoted at its outer end to an oscillatory member or lever 9, in 50 turn pivoted at its longitudinal center, as at 10, to the frame 1, said member being provided with a longitudinally-extending curved slot or guideway 11. Slidably and pivotally connected with the member 9 by means of a 55 pin 12, working in the guideway 11, is one end

of a connecting rod or link 13, the other end of which is pivotally connected with a valve-stem 14, in turn connected with a slide-valve of usual construction arranged within the steam-chest 15 and adapted for alternately 60 opening and closing suitable ports leading from said chest to the cylinder 5, the rod or link 13 being slidably disposed in an opening 16, provided in the projecting portion or ear 17, formed at one end of a rocking member or 65 bell-crank lever 18, pivoted at its elbow, as at 19, to the frame 1, and having the terminal of its other arm pivotally connected with one end of a connecting element or link 20, the other end of which is connected with an operating-lever 21, in turn pivoted to the frame and equipped with a spring-pawl 22, designed for engagement with a segmental rack 23. The rack 23 is provided with end sockets or 70 seats 24 25 and an intermediate socket 26, 75 any one of which may receive the pawl 22 for fixing the lever 21 against movement. The stem 14 is sustained by a guide member or bracket 27, bolted to the frame 1 and having outturned portions or ears 28, provided with 80 perforations 29 to receive the stem.

In practice steam is admitted to the chest 15 in the usual manner and thence through the ports to the cylinder 5 for operating the piston, it being understood that the latter is 85 operated owing to the steam being admitted alternately to the opposite ends thereof through the operation of the slide-valve, carried by the stem 14. The shaft 2 is rotated, as usual, through the medium of the pitman 90 4, connected therewith and with the piston, and as the shaft rotates it acts, by means of the eccentric-rod 8, for rocking the member 9 to reciprocate the valve-stem 14 through the intermediate link connection 13. When the 95 parts are in the full-line position illustrated in Fig. 1, with the connecting-pin 12 disposed at the lower end of the rocking member, the shaft 2 will be rotated in one direction. When, however, the lever 21 is swung rearwardly and the pawl 22 engaged with recess 24, the connecting-pin 12 of link 13 will, owing to the rocking of the lever 18 on its pivot, be moved to the other or upper end of the oscillatory member 9, thereby reversing 105 the direction of rotation of shaft 2. When the lever 21 is moved to an intermediate position, with the pawl 22 seated in the recess 26, as illustrated by dotted lines in Fig. 1, the rocking member or lever 18 and link 13 will 110

assume the dotted - line position shown in said figure, thereby bringing the connecting-pin 12 to a central position within the guide-opening 11, thus rendering the stem 14 and 5 its valve inoperative by the eccentric-rod 8 and stopping the operation of the engine. It is to be particularly observed that during operation the stem 14 will through the medium of the improved bracket be smoothly and 10 actively guided in its movements and that the portion 17 of the bell-crank 18 subserves the twofold function of guiding the connecting-rod 13 and presenting an efficient connection between the latter and the rocking member, whereby the rod may without injury be 15 positively moved for shifting its fulcrum in the member 9, it being understood that the rod 13 will have a sufficient amount of vertical play in the slot 16 to permit of its proper 20 movements through the medium of the rocking member 9.

From the foregoing it is apparent that I produce a simple reversing mechanism which may be readily installed and one whereby 25 the direction of rotation of the engine-shaft may be readily reversed or the engine stopped, it being understood that in attaining these ends minor changes in the details herein set forth may be resorted to without departing 30 from the spirit of the invention.

Having thus described the invention, what is claimed as new is—

The combination with an engine and its frame, of a movable valve-stem adapted for operating a valve to admit steam to the engine - cylinder, a bracket attached to the frame and having spaced perforated ears to receive and guide the valve-stem, a connecting-rod pivoted to the latter, a bell-crank lever pivoted on the frame and having a laterally-extending perforated ear through which the rod operates and by which the same is guided in its movements, an eccentric-rod operated by the engine-shaft, operative connections between the eccentric and connecting 45 rod, said connections including a pivoted rocking member having an arcuate slot in which one end of the connecting-rod is movably connected, and an operating-lever connected with the bell-crank lever for operating the same to shift the pivot of the connecting-rod within the slotted rocking member. 50

In testimony whereof I affix my signature in presence of two witnesses.

JOSEPH HANSER.
